BEDSPRING

Jacob N. Bressler, Detroit, Mich.

Application November 26, 1942, Serial No. 467,028

5 Claims. (Cl. 5—244)

This invention relates to a novel bed spring which is intended to supplant and replace the conventional metallic type, being constructed of a substituted material as for instance wood, plastic material, or other resilient substance.

Heretofore bed springs have been constructed generally of metal, which due to present conditions is difficult to obtain for that purpose.

It is the object herein to provide a bed spring constructed entirely of substituted material as for instance wood, plastic or other resilient non-metallic material.

It is the further object herein to provide a plurality of formed spring members interposed between the upper and lower portions of the bed 15 springs which are adapted to maintain a resilient and variably spaced relation therebetween.

The present invention therefore relates to the various elements hereinafter described and their various combinations as set out in the accompanying drawing of which—

Fig. 1 is a perspective view of the bed spring.

Fig. 2 is a top plan view of the upper frame

Fig. 3 is a plan view of the lower frame.

Fig. 4 is a side elevational view of the spring member.

Fig. 5 is a side elevational view of a slightly different embodiment.

Fig. 6 is an elevational view of one upper frame cross bar.

Fig. 7 is an elevational view of one notched lower frame cross bar.

It will be understood that the above drawing illustrates merely a preferable embodiment of the invention, and that other embodiments are contemplated within the scope of this invention.

Referring to the drawing the bed spring as a whole consists of a bottom supporting hollow frame 11 having cross bars 12, 13 and 14, and a top supporting frame 15 disposed in variably spaced relation thereto.

Cross bars 16, 17 and 18 are provisioned upon frames 15 providing intermediate supporting means for the longitudinally disposed slats 19 also secured upon and across said frame 15.

Spring members 20 shown in Fig. 4 are made preferably of wood with their ends 21 and 22 bent or looped inwardly and with the central portion 23 flexed or in convex shape as shown. It is contemplated that any other suitable resilient material could be employed which would be adapted to forming in substantially the shape shown in Fig. 4.

Referring to Fig. 1 a plurality of spring members 20, 20' and 20'', interposed in spaced relation

between the top supporting frame 15 and the bottom supporting frame 11, are also adapted to maintain a variably spaced relation between said frames. It is understood that springs 20 and 20'' may be employed as being sufficient depending upon the size of the bed springs, however any number may be employed in carrying out the present invention.

In construction the cross bars 16, 17 and 18 are notched at 24, 25 and 26 for respectively receiving the end portion 22, the central portion 23 and the other end portion 21 of the spring 20, any suitable means being employed for firmly and immovably securing said portions therein.

Spring 20 is also attached to the bottom supporting member 11, being secured within suitable notched portions 27 and 28 within the respective cross bars 12 and 14.

It will be also noted that the notches are sufficiently long and broad as to fully accommodate the depth and width of the spring member 20 whereby a secure construction is obtained.

It will be noted that leaf spring 20 is secured to the top frame 15 being interposed between said frame and the cross-bars 16, 17 and 18. Similarly spring 20 is secured to the bottom frame 11 being interposed between said frame and the cross bars 12 and 14.

Cross bars 12, 13 and 14 secured to bottom frame 11 are oppositely disposed in variably spaced relation respectively from the cross bars 16, 17 and 18 secured to the upper frame, whereby means are provided limiting the compression of spring 20, and preventing possible rupture or damage thereto, under any sudden extraordinary compressive stress.

Notched portions 24, 25, 26, 27 and 28 also perform the further function of retaining the springs 20, 20' and 20'' against any lateral movement, other than the expected torsional stresses that may be received when the bed spring is in use.

It will be understood that all the cross bars are similarly notched for accommodating and securing each of the other spring 20' and 20''. Furthermore the number of notches on any cross bar is naturally determined by the number of springs employed.

A slightly different embodiment is shown in Fig. 5 wherein the bottom frame is indicated at 29 with cross bars 30, 31, 32 and 33, cross bars 30 and 33 being notched at 34 and 35 to receive and secure the spring members 36 and 37.

The top frame 38 has secured thereto the cross bars 39, 40, 41 and 42, all respectively notched

at 43, 44, 45 and 46 to receive the end portions respectively of the springs 36 and 37.

In this embodiment two springs are employed instead of the unitary spring illustrated in Fig. 4; and in the place of the two oppositely disposed cross-bars 13 and 25 shown in Fig. 1, are employed the cross bars 31, 32, 40 and 41. It will be understood that the cross bars 30, 31, 32 and 33 and cross bars 39, 40, 41 and 42 are oppositely disposed in variably spaced relation and provide limiting means against extreme compression or distortion of the springs 36 and 37.

Likewise it will be understood that the notched portions 34 and 35 and also portions 43, 44, 45 and 46 are designed to provide means for snugly attaching spring members 36 and 37 between the top frame 38 and the bottom frame 29.

It will be understood that the present invention is adaptable also for the construction and manufacture of furniture.

Having described my invention, reference should now be had to the claims which follow for determining the scope thereof.

I claim:

1. A bed spring comprised of an upper supporting frame, a central cross bar and cross bars secured adjacent the ends thereof, a lower supporting frame, a central cross bar and cross bars secured adjacent the ends thereof, and a plurality of unitary longitudinally extending springs interposed between said frames, each spring consisting of a substantially flat member inwardly and upwardly bent at its ends into substantially semi-circles, and with the intermediate portion upwardly curved, the ends and central portion thereof being secured between said upper frame and its cross bars, said spring being also secured between said lower frame and its end cross bars at points intermediate said ends and said central portion.

2. A bed spring comprised of an upper supporting frame, a central cross bar and cross bars secured adjacent the ends thereof, a lower supporting frame, a central cross bar and cross bars secured adjacent the ends thereof, and a plurality of unitary longitudinally extending springs interposed between said frames, each spring consisting of a substantially flat member inwardly and upwardly bent at its ends into substantially semi-circles, and with the intermediate portion upwardly curved, the ends of said spring being secured to the end cross bars of the upper frame, and the central portion of said spring being secured to the central cross bar of said upper frame,

said spring being also secured to said end cross bars on the lower frame at the points where said springs are inwardly bent.

3. A bed spring comprised of an upper supporting frame, a central cross bar and cross bars secured adjacent the ends thereof, a lower supporting frame, a central cross bar and cross bars secured adjacent the ends thereof, and a plurality of unitary longitudinally extending springs interposed between said frames, each spring consisting of a substantially flat member inwardly and upwardly bent at its ends into substantially semi-circles, and with the intermediate portion upwardly curved, the ends and central portion thereof being secured between said upper frame and its cross bars, said spring being also secured between said lower frame and its end cross bars at points intermediate said ends and said central portion, the end cross bars and the central cross bars on said frames being oppositely disposed in spaced relation to limit the flexing movement of said spring.

4. A bed spring comprised of an upper supporting frame, a central cross bar and cross bars secured adjacent the ends thereof, a lower supporting frame, a central cross bar and cross bars secured adjacent the ends thereof, and a plurality of unitary longitudinally extending springs interposed between said frames, each spring consisting of a substantially flat member inwardly and upwardly bent at its ends into substantially semi-circles, and with the intermediate portion upwardly curved, said cross bars being notched adjacent said frames, the ends of said spring and the central portion thereof being secured within the notches of said cross bars on said upper frame, said spring being also secured within the notches of the end cross bars of said lower frame at points intermediate said ends and said central portion.

5. A bed spring comprised of an upper supporting frame, a plurality of cross bars thereon, a lower supporting frame, a plurality of cross bars thereon, and a plurality of unitary longitudinally extending springs interposed between said frames, each spring consisting of a substantially flat member inwardly and upwardly bent, at its ends, into substantially semi-circles, with the intermediate portion upwardly curved, the ends and central portion thereof being secured to the upper frame cross bars, said spring being also secured to the lower frame cross bars at points intermediate said ends and said central portion.

JACOB N. BRESSLER.
